MILL FOR REDUCING METAL STOCK

George Bertram Coe, Upper Montclair, N. J., assignor to Tube Reducing Corporation, Stamford, Conn., a corporation of Delaware

Application November 5, 1949, Serial No. 125,770

11 Claims. (Cl. 80—14)

1

The above named applicant has made an invention or discovery of which the following is a specification.

The present invention relates to improvements in mills of the type shown in my Letters Patent No. 1,952,841, that is to say, to mills for the cold reduction of metal stock, such as tubes or rods, wherein the stock to be reduced is fed intermittently, step by step, to the reducing devices which act upon the stock while cold to reduce it in diameter and, in the case of tubular stock, to reduce it in diameter or gage or both. In such mills, as in that of my Letters Patent aforesaid as well as in the mill shown and described here, the reducing devices generally comprise a single pair of oscillating die-rolls mounted on a reciprocating carriage so that on each forward stroke of the carriage they roll upon a short section of the stock while the latter is stationary, and on each rearward stroke of the carriage roll back again upon that same section of stock, whereupon the stock is then given an increment of feed to advance it between the rolls before the next reciprocation of the carriage occurs. Thus, for each cycle of the die-rolls, there is an increment of feed; and, in addition, the stock (and also the mandrel which is generally used in the case of tubular stock) is given about a quarter turn about its axis. This quarter turn usually occurs in the interval directly following the forward stroke of the carriage and before its backward stroke begins, and the increment of feed takes place in the interval directly following the backward stroke; and since during each of said intervals the movement of the carriage is reversed in direction, the latter during each said interval is momentarily stationary.

Since the efficiency of these mills depends, in large part, upon the speed at which it is practicable to operate them, it is obvious that their efficiency will, in turn, depend upon the rapidity at which the mechanisms provided for feeding the stock and for turning the stock and mandrel, can be made to operate smoothly and effectively during the relatively short intervals while the carriage is stationary; for it is the operation of those said mechanisms which limits the time allowable between the respective strokes of the carriage. The principal object of the present invention, accordingly, is to relieve this "bottle-neck," so to speak, in this type of mill, by providing an improved mechanism for feeding the stock to the rolls, and an improved mechanism for turning the stock and the mandrel. Other objects are to provide a fluid system

2

for operating these mechanisms and other parts of the mill, and to coordinate the fluid system with the driving mechanism for the rolls and carriage.

5 The said improved mechanisms and fluid system have been incorporated in the mill shown in the accompanying drawings wherein Figs. 1, 1A and 1B are plan views respectively of the front, rear and intermediate portions of the mill; 10 Figs. 2, 2A and 2B side elevations of the same portions corresponding respectively to Figs. 1, 1A and 1B; Figs. 3 and 4 larger scale views in plan and vertical section respectively of the intermediate portion of the mill, the plane of the sectional view being indicated by the line 4—4 in Fig. 3; Fig. 5 a view partly in elevation and partly in section on a plane indicated by the line 5—5 in Fig. 4; Fig. 6 a detail section the plane of which is indicated by the line 6—6 in Fig. 3; Fig. 15 7 an enlarged scale view partly in elevation and partly in section, the plane of the section being indicated by the line 7—7 in Fig. 1; Figs. 8 and 9 detail sectional views taken respectively on planes indicated by the lines 8—8 and 9—9 in Fig. 7; 20 Fig. 10 a view partly in elevation and partly in section, the plane of the section being indicated by the line 10—10 in Fig. 2; Figs. 11, 12 and 13 similar views on a larger scale taken on planes indicated respectively by the lines 11—11 in Fig. 1, 12—12 in Fig. 1B and 13—13 in Fig. 1; Fig. 14 25 a section taken on a plane indicated by the line 14—14 in Fig. 11; and Fig. 15 a diagram of the fluid system by which certain parts of the mill are operated, and showing the relation of the fluid motors, the fluid circuits and the control valves in said system, to the timing cam and the fluid reservoir.

30 The reducing devices here shown comprise a pair of die-rolls 20 (Figs. 11 and 14) mounted for oscillation in a reciprocating carriage 21 and being geared together by two pairs of gears 22. A pair of gears 23 rigidly connected respectively to the gears of one of the pairs 22, mesh respectively with racks 24 secured, one on each side of the carriage, to the frame of the mill whereby, 35 as the carriage reciprocates on the frame, the rolls will be oscillated. Secured, at each side of the carriage, to the upper part of the mill frame are tracks 25 which run lengthwise of the frame and from which the carriage is suspended, said carriage being supported on said tracks by bearing rollers 26 journaled on heavy studs 27 fast to the carriage fore and aft and on each side thereof, so that as the carriage is reciprocated said rollers travel back and forth upon said

tracks. Fast to each roller 26 so as to rotate therewith are gears 28, these gears meshing respectively with other racks 29 also secured, one at each side of the carriage, to the mill frame so as to extend along and beside said tracks, the purpose of these gears 28 and racks 29 being to prevent slippage of said rollers on their tracks and the resultant wear and consequent flattening of the peripheries of these rollers when the carriage reverses the direction of its movement at the end of each half cycle of its reciprocation.

The carriage is reciprocated by the main driving motor 30, the shaft of which is directly coupled to the main driving shaft 31 (Figs. 1 and 2) whereby said shaft is driven at the same speed as the motor shaft. Fast on said main shaft is a relatively small pinion 32 which is connected by gears 32' to a relatively large gear 33 fast on a countershaft 34. On one side of the large gear 33 a crank arm 35 is attached to said countershaft, and a connecting rod or link 36 connects the crank arm to the lower end of a rock arm 37 fulcrumed at 38 on the front end of the mill frame forward of the die-roll carriage. As shown in Figs. 2, 10 and 11, the upper end of this rock arm is forked and each fork is so connected to the forward end of the carriage 21 by links 39 that the pivotal connections 40—40 of these links to the carriage and rock-arm lie substantially in the horizontal plane C—D (Fig. 11) in which the opposing faces of the die-rolls meet, and which plane is coincident with the axes of mandrel M and the stock S. Thus, during the forward or working stroke of the carriage and die-rolls, the links 39 are under tension rather than under compression and the carriage is pulled forward rather than pushed forward during the working stroke. Where, as heretofore, the carriage is pushed rather than pulled during its working stroke, there is a tendency of the forward bearing rollers 26 to lift from their supporting tracks 25 and unless the mill is run at very slow speed, this produces a whipping action of the rollers upon the tracks and not only causes excessive vibration but also excessive wear and tear on the rollers and tracks thus requiring them to be replaced frequently. By driving the carriage in the manner above described this tendency is counteracted. To provide sufficient operating space for the large gear 33 and its associated crank arm 35 and connecting rod 36 and leave ample room for the reciprocation of the die-roll carriage, said gear and connecting rod may be disposed below a horizontal plane passing through or near the base plate of the mill (Fig. 2) so that they may be housed in a pit underneath the main body of the mill and below the floor level of the room wherein the mill is installed.

The stock S which may be either tubular or solid and which, for purposes of description and illustration, will be assumed to be tubular as shown in the drawings, is gripped and held at its rear end by a chuck 41 (Figs. 13, 2B and 12) rotatable in a longitudinally movable head 42 which is engaged by the forward end of a longitudinally movable but non-rotatable threaded shaft 43 (Figs. 3 and 4) housed within a cylindrical casing 44. Threaded to this shaft is a feed-nut 45 (Figs. 4 and 5) mounted for rotation in a bracket 46 on the mill frame and restrained thereby from movement in an axial direction, a gear 47 through which said nut is rotated being secured to its rear end. The mechanism just described, namely the parts 41 to 47 inclusive, comprise the feeding mechanism for the stock;

and this mechanism is operated by the fluid system, hereinafter described, to advance the stock step by step to and between the die-rolls.

As previously explained, the stock and, in the case of tubular stock where a mandrel is used to assist in reducing the same, the mandrel as well as the stock are turned about their axes 90°, more or less, during each short interval when the die-roll carriage is stationary immediately prior to the beginning of its forward or working stroke. The mandrel, denoted at M in Fig. 11, is adapted to be attached to the forward end of a mandrel-rod M' (Figs. 1B and 4); but herein-after the term mandrel, when that term is used, will be understood to include both the mandrel per se and the rod M' to which it is attached. During the reduction of the stock, the mandrel, except for its intermittent turning movement, is otherwise stationary, being firmly held at its rear end against the rearward thrust of the die-rolls, by a bearing block 48 in which its rear end is journaled, the said block being secured to a slideable carriage 49 which, while the stock is being fed forward along the mandrel to the die-rolls, is rigidly held by latch-slides 49' against displacement by the backward thrust of the die-rolls (Fig. 3). The mechanism which imparts to the mandrel, as well as to the stock, their intermittent turning movements aforesaid comprises a rotatable shaft 50 having an extension 51 coupled to its rear end; and said shaft is journaled at its rear end in the frame member 53 (Fig. 4) and has a gear 54, through which it is turned, fast on its forward end (Fig. 2) and a gear 55 fast on its rear end. The gear 55 meshes with an idler gear 56 which, in turn, meshes with a gear 57 integral with the journal 58, which is rigidly secured to the rear end of the mandrel. In addition, the said turning mechanism includes a gear 59 (Fig. 12) carried by the movable head 42 and splined to the shaft 50 so as to be movable along said shaft, and this gear meshes with an idler gear 60 also carried by the head 42, the latter gear, in turn, meshing with a gear 61 fast on the rotatable chuck 41 which, as before stated, grips and holds the rear end of the stock S. Thus, when the shaft 50 is turned by the gear 54, the mandrel and stock will be turned at the same time and in the same direction and degree by the gears 55, 56 and 57 and the gears 59, 60 and 61 respectively. The stock and mandrel turning mechanism, like the stock feeding mechanism, is operated by the fluid system alluded to above and presently to be described.

In Figs. 3, 4 and 5 the mandrel M and the threaded feed-shaft 43 are shown in operative position in relation to a length of stock which is being reduced. When this length of stock has been fed forward far enough to bring its rear end a short distance from the reducing rolls, it is released from the jaws 62 (Fig. 12) of the chuck 41 by turning a hand-wheel 63 (Fig. 1B) fast on a threaded shaft 64 meshing with a worm 65, thereby loosening the grip of the jaws on the stock; and a fresh length of stock may then be introduced into the mill for reduction. To introduce this new length of stock, the feed-nut 45 is first rapidly rotated, by means herein-after described, in a direction reverse to that of its rotation for feeding the stock forward to the reducing rolls, thus causing the feed-shaft 43 and its attached head 42 to be returned to their starting positions; and the mandrel is drawn rearwardly from its position shown in

Fig. 4 to its position shown in Fig. 2A, by an endless chain 66, after withdrawing the latch-slides 49' from their locking engagement with the sliding carriage 49. The chain 66, which is secured to said carriage at 67, passes over sprockets 68, 68', the latter of which is fast on one end of a shaft 69 to the other end of which a gear 70 is secured and driven by an auxiliary motor 115 (Figs. 3 and 5). To sustain the free end of the mandrel when the latter is in its rearward position, a support 72 freely movable along a track 73 may be provided in a position to be engaged by a lug 74 on said chain and moved rearwardly thereby to support the mandrel at or near its forward end when the mandrel has reached its rearward position.

Having withdrawn the mandrel to its rearward position and having returned the feed-shaft 43 and its attached head 42 to their starting positions, the fresh length of stock is now introduced, its rear end shoved into the jaws of the chuck 41, and the hand-wheel 63 turned to tighten the jaws on the stock; then the motor 115 is again operated, this time in the reverse direction, to push the mandrel forward through the stock and thus restore the mandrel to its operative position. The latch-slides 49' are then moved into position to engage the carriage 49, and the mill is again ready for further operation. The movement of the latch-slides, both into and out of their latching positions, is effected by the pistons of cylinders 76 to which these slides are respectively secured and which, together with the motor 115, are operated by the fluid system before alluded to as will presently be explained.

When the introduction of a fresh length of stock has been completed and the mandrel restored to its operative position, the forward end of the fresh length of stock is adjacent to or abuts against the rear end of the previous length of stock S' which is still in the mill, so that as the mill is now operated the feeding forward of the new length of stock causes the previous length also to be fed forward until the reduction of the latter is complete. However, since this previous length is no longer gripped and held by the jaws of the rotatable chuck 41, it will not be subjected to the action of the turning mechanism previously described. Accordingly additional turning mechanism is provided for gripping and holding the out-going previous length of stock. For this purpose, a second rotatable chuck 77 is provided (Fig. 13) forward of the reducing rolls and to which a gear 78 is connected to turn this chuck intermittently the same as in the case of the chuck 41 previously referred to. The jaws 79 of said second chuck 77 are at all times, during the normal operation of the mill, held in sufficient frictional engagement with the outgoing previous length of stock S' to cause the latter to be turned by the gear 78 and, notwithstanding the frictional grip of said jaws, permit said stock to be fed forward through the engagement of its rear end by the forward end of the new length of stock. As shown in Fig. 13, this second chuck has a sleeve 80 and a collar 81 attached to said sleeve and through both of which the outgoing previous length of stock S' passes, the said jaws 79 being retained between said sleeve and collar and within a wedge-ring 82. The gear 78 is slidably keyed to the sleeve 80 so that if it is desired for any reason to relax the grip of the jaws on the stock S', this can be done by giving the sleeve a slight sliding movement through said gear 78

in a rearward direction; and this sliding movement of the sleeve may be effected by admitting fluid under pressure to a cylinder 83 having a piston connected to a rod 84 whereby the latter, when moved by the piston against the action of a spring 85, rocks a lever 86 fulcrumed on the mill frame. The lever 86 is connected by a clevis 87 to said sleeve so that when said rod is moved by said piston against the action of said spring, the jaws will release the stock but are otherwise continuously held by said spring in frictional engagement with the stock.

The said fluid system will now be described, and first those parts of this system which operate the stock and mandrel turning mechanism and the stock feeding mechanism; and since these said parts of said system are to operate in synchronism with the die-rolls, their actuation may be controlled by a cam 90 (Figs. 1, 7, 8 and 15) which is fast on the countershaft 34 and which reciprocates a slide 91 in a casing or box 92 secured to the mill frame. Referring more particularly to the diagram of Fig. 15, the parts of said fluid system for operating the turning mechanism for the mandrel and stock and also the turning mechanism for the out-going previous length of stock, comprise a pair of hydraulic rams 93, 93' secured to the mill frame and having their respective plungers directly connected at 94 to one end of the cam slide 91 and their respective cylinders communicating, through pipes 95, 95', with the respective intake ports of a pair of fluid-operated motors 96, 96'. The respective outlet ports of these motors are connected to a reservoir 97 for oil or other fluid used in the system, by pipes 98, 98'. Return pipes 99, 99' are provided to directly connect the reservoir with the respective cylinders of said pair of rams to complete the fluid circuits through said motors; and each 40 of said pipes 99, 99' has a check-valve therein to prevent backward flow from said cylinders to the reservoir. The other end of the cam-slide 91 is operatively connected to a single hydraulic ram 100 on the mill frame, by a linkage which, as 45 here shown, includes a member such as a clevis 101 directly secured to the cam-slide, a lever 102 fulcrumed on the mill frame, a link 103 connecting the clevis to one end of said lever, a block 104 slidably supported on the mill frame and directly connected to the plunger 100' of the ram 100, and a link 105 connecting this slide or block 104 to the other end of said lever. To change the 50 relative lengths of the arms of said lever so as to adjust the length of stroke of the plunger 100' to that desired, the fulcrum of said lever may consist of a trunnion 106 slidable along said lever and the frame and to which an adjusting screw 107 is threaded, and nuts 108 to clamp the trunnion to the lever and frame in its adjusted position; and to support the lever while said adjustment is being made, a link 109 is provided, one end of which is pivoted to the frame and its other end connected to the lower end of said lever by a pivot or connecting pin 110 which is fitted to 55 and passes through bores in the link 109 and lever respectively. To prevent the parts just described from cramping during the operation of the mill, the diameter of the bore in the link 109 through which the connecting pin 110 passes, is greater than the diameter of the bore for said pin in the lower end of said lever (Fig. 9).

The parts of the fluid system for operating the turning mechanism include the ram 100 aforesaid and its plunger 100', a pipe 110 connecting the cylinder of that ram with the intake port of

a fluid-operated motor 112, a pipe 113 connecting the outlet port of that motor with the reservoir 97, and a return pipe 114 having a check-valve therein and directly connecting the reservoir with the cylinder of ram 100.

The motor 112 is operatively connected to the gear 47 on the feed-nut 45 of the stock feeding mechanism, the motor 96 is operatively connected to the shaft 59 of the stock and mandrel turning mechanism, and the motor 96' is operatively connected to the gear 78 by which the outgoing previous length of stock is turned. And as indicated in the diagram of Fig. 15, the cylinders of the rams 100, 93 and 93' by which the motors 112, 96 and 96' are respectively actuated, are disposed below the reservoir 97. The latter is an open reservoir, i. e. the fluid therein is not under pressure and thus is free to flow by gravity through the respective pipes 114, 99 and 99' to said cylinders to keep them filled and so maintain the rams in operative condition at all times. Hence, since there is no back-pressure from the reservoir to resist the flow of fluid through said motors and back to the reservoir, and since these motors are, and remain, continuously in operative engagement with the respective feeding and turning mechanisms 45, 59 and 78, the latter are instantly responsive to the action of the rams.

In addition to the motors 96, 96' and 112, the fluid-operated motor 115 is included in the fluid system, for driving the chain 66. For this purpose, fluid from the reservoir is delivered to said motor 115 by a pump 116, driven by an auxiliary motor 117, and having a pressure-relief valve (not shown) opening into the reservoir. A pipe 118 connects the discharge end of said pump to one side of a 4-way valve 119, a return pipe 120 connects the opposite side of said valve to the reservoir, and pipes 121 connect said valve to the respective ports of the motor 115, whereby in one position of the 4-way valve, said pump will cause fluid to flow through said motor in a direction to move the chain 66 so as to draw the sliding carriage 49 and mandrel rearwardly, while, in another position of said 4-way valve, the pump will cause fluid to flow through said motor in the reverse direction to return the mandrel again to said operative position. It will of course be understood that before the carriage 49 can be drawn rearwardly, the latch-slides 49' must be withdrawn from their locking positions with the carriage; and to effect this, power is supplied from the pump 116 to the aforesaid cylinders 76 through a pair of 4-way valves 122 (only one of which is shown in the drawings, Fig. 15). Pipes 123 connect one side of each of said pair of valves 122 to the discharge end of said pump, return pipes 124 connect the opposite sides of said pair of valves 122 to the reservoir, and pipes 125 connect said pair of valves 122 to each end of the respective cylinders 76, whereby fluid is caused to be delivered to either end of said cylinders to move their pistons and attached latch-slides in one direction or the other for locking and unlocking the sliding-carriage 49. Each of the three 4-way valves 119, 122 has three positions, namely, a closed position which shuts off all flow through the valve, and two open positions one of which, designated as open position I, permits flow in one direction either to the motor 115 to draw the mandrel rearwardly or to the cylinders 76 to withdraw the latch-slides, and the other of which open positions, designated as

open position II, permits flow either to said motor or to said cylinders in the reverse direction to restore the mandrel to its operative position or to bring the latch-slides into locking engagement again with the carriage 49. When said carriage is to be moved to draw the mandrel rearwardly, the valve 119 is first set in its closed position and both of the valves 122 in their open positions I, and the pump 116 started in operation, whereby the latch-slides 49' will be withdrawn from their locking position with the carriage 49; then both of the valves 122 are shifted to their closed positions and the valve 119 to its open position I, whereby the motor 115 will cause the carriage 49 and mandrel to move rearwardly. To return the mandrel to its operative position again, the valve 119 is set to its open position II, while both of the valves 122 are left in their closed positions; and after the mandrel has thus been restored to its operative position, the valve 119 is shifted to its closed position and both of the valves 122 to their open positions II, whereby the latch-slides will be moved into position again to lock the carriage 49, and the pump is then stopped.

For rapidly returning the feed-shaft 43 to its starting position, an additional pump 126, similar to the pump 116, is provided in the fluid system and also adapted to be driven by said auxiliary motor 117. The intake of this pump, like that of pump 116, is connected to the reservoir. A pipe 127 connects the discharge end of this pump 126 to one side of a 3-way valve 127' the opposite side of which is connected to the aforesaid outlet port of the fluid-operated motor 112. The inlet port of said motor 112 is connected to one side of a second 3-way valve 110' the opposite side of which is connected to the pipe 118 leading from the cylinder of ram 100. Each of these 3-way valves is connected to the reservoir by the pipe 113 aforesaid and each said valve has two positions which may be designated as position I and position II respectively. When, as indicated in Fig. 15, the valve 110 is in position I and the valve 127' in position II, fluid impelled by the ram 100 will pass through the motor 112 in one direction while the pump 126 is cut off from said motor; when the valve 110' is shifted to position II and the valve 127' to position I, fluid impelled by the pump 126 will pass through said motor in the reverse direction while the ram 100 is cut off from said motor. Thus, when the feed-shaft 43 is to be returned to its starting position, the valve 110' is adjusted to position II and the valve 127' to position I and the pump 126 started in operation; and after the feed-shaft has been restored to its starting position, the pump 126 is stopped and the valve 127' shifted back to position II and valve 110' to position I again.

While the fluid-operated motors 112, 96 and 96' are preferably of the rotary type such as that commercially known as Vickers constant displacement type fluid motor, they, as well as the fluid-operated motor 115, may be of any rotary type or, indeed, of a non-rotary type such, for example, as the cylinder and piston type shown herein for operating the latch-slides 49'. Hence, the term fluid-operated motor, wherever used herein, is not to be construed in a literal or restrictive sense.

I claim as my invention:

1. In a mill for reducing metal stock and having stock feeding mechanism which includes a feed-shaft and an axially immovable feed-nut

threaded thereon to advance the feed-shaft, and said mill also having a fluid system for operating said stock feeding mechanism, said fluid system including a reservoir for the fluid, a ram, a fluid-operated motor operatively connected to the feed-nut to rotate the latter, a pipe connecting the cylinder of the ram with the intake port of the motor, a pipe connecting the outlet port of the motor with the reservoir, a return pipe having a check-valve therein and connecting the reservoir with the cylinder of the ram, a pump the intake end of which is connected to the reservoir, a pipe connecting the discharge end of the pump with the outlet port of the motor, a pipe connecting the intake port of the motor with the reservoir, and control valves in the first, second, fourth and fifth named pipes, whereby said valves may be set either to cause fluid impelled by the ram to pass through the motor in one direction to advance the feed-shaft or to cause fluid impelled by the pump to pass through the motor in the reverse direction to return the feed-shaft to its starting position.

2. The mill defined in claim 1 and in which the said control valves comprise a pair of 3-way valves one of which is placed in the first and fifth named pipes to control their connection with the inlet port of the motor and the other of which is placed in the second and fourth named pipes to control their connection with the outlet port of the motor.

3. In a mill for reducing tubular metal stock, the combination with a reciprocating carriage, a mandrel mounted on the carriage, a mechanism for feeding the stock along the mandrel to the reducing devices, mechanism for turning both the stock and the mandrel about their axes, means to reciprocate the carriage, a slidable carriage upon which the mandrel is mounted, and latches for locking the slidable carriage to hold the mandrel in its operative position, of a fluid system for operating said stock feeding mechanism, said stock and mandrel turning mechanism, said slidable carriage, and said latches, and characterized by a fluid reservoir, a fluid-operated motor for operating the stock feeding mechanism, a hydraulic ram, a pipe connecting the cylinder of said ram with the intake port of said motor, a pipe connecting the outlet port of said motor with the reservoir, a return pipe connecting the reservoir with the cylinder of said ram and having a check-valve to prevent the backflow of fluid from that cylinder to the reservoir, operative connections between said motor and the stock feeding mechanism, a second hydraulic ram, a second fluid-operated motor, a pipe connecting the cylinder of said second ram with the intake port of said second motor, a pipe connecting the outlet port of said second motor with the reservoir, a return pipe connecting the reservoir with the cylinder of said second ram and having a check-valve to prevent backflow of fluid from that cylinder to the reservoir, operative connections between said second motor and the stock and mandrel turning mechanism, a third fluid-operated motor operatively connected to said slidable carriage, a pump the intake of which is connected to the reservoir, a 4-way valve, a pipe connecting the discharge end of said pump to one side of said 4-way valve, a pipe connecting the opposite side of said 4-way valve with the reservoir, pipes from said 4-way valve to the respective ports of said third motor, fluid-operated cylinders the pistons of which are at-

tached to said latches, a pair of 4-way valves, pipes connecting the discharge end of said pump respectively to one side of each of said pair of 4-way valves, return pipes connecting the opposite side of each of said pair of 4-way valves respectively with the reservoir, pipes from each of said pair of 4-way valves to the respective ends of said fluid-operated cylinders, and means for synchronizing the operation of said rams with each other and with the reciprocating carriage.

4. A fluid system for controlling the operation of the stock feeding and stock turning mechanisms of a mill of the type described and having a timing cam, which system comprises a fluid-operated motor in continuous operative engagement with the feeding mechanism and provided with a fluid inlet port and a separate fluid outlet port, a hydraulic ram, a reservoir for fluid, a pipe connecting the reservoir with the cylinder of said ram, said reservoir being open to the atmosphere and disposed above said ram so that fluid may freely flow by gravity through said pipe from the reservoir to the cylinder of said ram, a check valve in said pipe to prevent backward flow of fluid through said pipe to the reservoir, a pipe connecting the cylinder of said ram to the inlet port of said motor, a pipe connecting the outlet port of said motor with the reservoir, a second fluid-operated motor in continuous operative engagement with the turning mechanism and provided with a fluid inlet port and a separate fluid outlet port, a second hydraulic ram disposed below the reservoir, a pipe connecting the reservoir and the cylinder of said second ram for the flow of fluid to the latter and having a check valve to prevent backward flow to the reservoir, a pipe connecting the cylinder of said second ram to the inlet port of said second motor, a pipe connecting the outlet port of said second motor with the reservoir, operative connections between the plunger of the first named ram and the timing cam, and operative connections between the plunger of said second ram and the timing cam.

5. The fluid system defined in claim 4 and further characterized by a third fluid-operated motor in continuous operative engagement with another of said turning mechanisms and provided with a fluid inlet port and a separate fluid outlet port, a third hydraulic ram disposed below the reservoir, a pipe connecting the reservoir and the cylinder of said third ram for the flow of fluid to the latter and having a check valve to prevent backward flow to the reservoir, a pipe connecting the cylinder of said third ram to the inlet port of said third motor, a pipe connecting the outlet port of said third motor with the reservoir, and operative connections between the plunger of said third ram and the timing cam.

6. The fluid system described in claim 4 and further characterized by this: that the operative connections between the plunger of the first named ram and the timing cam include a lever fulcrumed to the frame of the mill and having means to vary the relative lengths of its arms.

7. The fluid system defined in claim 4 and further characterized by this: that the connections between the plunger of the first named ram and timing cam and between the plunger of said second ram and timing cam include a slide reciprocated by the timing cam, that one end of said slide is directly connected to the plunger of said second ram and that the other end of said slide is connected to the plunger of the other ram by a linkage including a lever fulcrumed to the frame

and having means to vary the relative lengths of its arms.

8. The fluid system defined in claim 4 and further characterized by this: that the operative connections between the first named ram and the timing cam include a slide reciprocated by said cam, a member fast to said slide, a lever, a link connecting said member to one end of said lever, a trunnion adjustable on said lever to vary the relative lengths of the lever arms, means to clamp the trunnion to both the lever and the frame of the mill, a slide fast to the plunger of said first named ram, and a link connecting the last named slide to the other end of said lever.

9. The fluid system defined in claim 4 and further characterized by this: that the stock feeding mechanism comprises a longitudinally movable head, a chuck carried thereby for gripping and holding the stock, a non-rotatable threaded shaft the forward end of which engages the head, a feed-nut threaded to the non-rotatable shaft and restrained from movement in an axial direction, and a gear on the feed-nut operatively connected to the first named motor.

10. The fluid system defined in claim 4 and further characterized by this: that a rotatable chuck is provided to grip and hold the stock and

that the stock turning mechanism comprises a rotatable shaft geared to the chuck and operatively connected to said second motor.

11. The fluid system defined in claim 4 and further characterized by this: that the stock feeding mechanism comprises a longitudinally movable head, a rotatable chuck carried thereby for gripping and holding the stock, a non-rotatable threaded shaft engaging the head, a feed-nut threaded to the non-rotatable shaft and restrained from movement in an axial direction, that the stock turning mechanism comprises a rotatable shaft geared to said chuck, and that said feed-nut is operatively connected to the first named motor and said rotatable shaft geared to said second motor.
